MANUFACTURE OF SHOES

Edward H. Woodberry, Solvay, N. Y., assignor to
The Lamson Company, Syracuse, N. Y., a cor-
poration of Massachusetts

Application May 26, 1939, Serial No. 275,812

2 Claims. (Cl. 12—142)

In the manufacture of shoes the addition of moisture is necessary in order that the shoes be in the correct temper, i. e., the proper degree of softness, flexibility and workability, for each operation in the process of manufacture. Inasmuch as succeeding operations of manufacture require progressively drier leather, the shoes are moistened at the beginning of the manufacture and the moisture content therein is reduced by partially drying the leather after such operations as stretching the upper over the last, attaching the sole to the lasted upper, pressing or leveling the sole, attaching the heel, edge and heel-making, bottom sanding, etc., until toward the end of the process, before bottom finishing, the leather should be practically dry to be in correct temper.

The importance of having the shoe in the correct temper, neither too wet nor too dry, at any particular operation cannot be overemphasized inasmuch as on its particular condition depends the shape and fit of the upper, the form and tread of the sole, the smoothness and regularity of the edge and the quality and uniformity of the bottom.

The usual practice in the past has been to allow the shoes to remain on drying racks open to the atmosphere or in crude "dry houses" until the shoes looked or seemed to be in the proper temper. However, the procedure required so much floor space and time in process and resulted in such an accumulation of work in process that modern manufacturing and marketing conditions have made artificial drying necessary. Also, owing to variation in atmospheric humidity, work in process, and the inaccuracy of human determination of the correct temper, the shoes were often too wet or too dry for proper operation, with a consequent detriment to the quality of the finished shoes. It has been proposed to substitute dehumidified air for atmospheric air in the drying stages, flowing the air through tunnels along which the shoes are conveyed from station to station, but the cost of producing adequate volumes of dryer air plus the expense of adequately controlling its humidity is prohibitive in most factories.

Objects of the present invention are to avoid the wastes of time, needless investment and floor space incident to the rack drying system, to avoid the high cost of dehumidifying the drying air, to reduce the time allotted to drying stages, to insure a positive drying system by which the shoes are presented to the workmen in the correct temper automatically without depending on fallible human determination, to allow for the

uncontrolled drying which inevitably takes place while work operations are being performed between successive drying stages, and to accomplish the foregoing positively, automatically and constantly day after day regardless of variations in humidity and temperature of atmospheric air.

According to this invention a detailed survey of each particular factory is made prior to installation of the equipment. The results of the survey determine the exact moisture content required in the shoe at each point in the process, the normal rate of moisture loss in open air during the normal fabrication of the shoe, and all this at any particular set of atmospheric conditions. Thus the points at which artificial drying must be introduced and the amounts of moisture that must be removed at each point with any particular set of atmospheric conditions are determined. Knowing the rate of drying and the amount of moisture that must be removed at any point in the process, it is a simple matter to compute the correct drying time for the particular atmospheric conditions under which the tests are made.

The problem then resolves itself into setting up a system that will keep the predetermined rate of drying relatively constant as atmospheric conditions vary. To do this I determine corrective factors corresponding to various combinations of atmospheric temperature and relative humidity for controlling the degree of moisture removal in each dryer. I then regulate the extent of drying in each dryer according to those predetermined corrective factors which correspond to the then existing atmospheric temperature and relative humidity, thereby insuring that the shoes leave the dryer in the same degree of temper regardless of atmospheric conditions.

The extent of drying may be regulated in various ways as by varying the time of drying or the velocity of the air through the dryer. However, in most cases it is preferable to hold the drying time and air velocity constant and to control the drying effect by regulating the temperature of the air in the dryers. To indicate the correct temperature of the air in each dryer corresponding to each combination of atmospheric temperature and relative humidity I prepare a chart for each dryer, each chart comprising vertical and horizontal rows corresponding to different atmospheric temperatures and relative humidities. Thus, if the vertical rows correspond to different atmospheric temperatures, the horizontal rows correspond to different degrees of relative humidity. To regulate a dryer the then existing temperature and relative humidity of

the atmosphere are determined with an ordinary thermometer and humidostat and the operator locates on the chart the vertical and horizontal columns corresponding to then existing atmospheric temperature and relative humidity. At the intersection of the two columns, he finds the number which indicates the proper setting of the dryer under those conditions of atmospheric temperature and relative humidity. The numbers on the chart may indicate the air temperatures in the dryer or they may be merely arbitrary figures which indicate how the dryer regulator should be set.

The numbers on the chart involve corrective factors by which the drying effect may be maintained constant under different atmospheric conditions. In general the corrective factors involve an increase of dryer temperature with an increase of either atmospheric temperature or atmospheric humidity and vice versa for each dryer.

Changes in atmospheric conditions influence the drying of the shoes in various ways. The principal effect is to vary evaporation from the shoes. Thus on a humid day the evaporation would ordinarily be slower than on a dry day (other conditions remaining the same). A secondary effect is to vary the rate of drying during the operating intervals between the drying stages since, while a particular operation is being performed, the shoes are slowly drying in the open air. On a humid day this drying is retarded and consequently more moisture must be removed in the succeeding drying stage to afford the proper temper for the next operation. For this reason the aforesaid corrective factors preferably include a correction for variations in open-air drying under different atmospheric conditions.

Varying the temperature of the air in each dryer introduces still another variable, namely, a variation in the rate at which moisture feeds to the surface of the leather while in the dryer. The hotter the leather the faster the moisture moves to the surface of the leather to be carried away by the heated air in the dryer. Hence, as the humidity of the atmosphere increases the temperature in the dryer need not be increased as much as it would be if the capillary feed of moisture to the surface of the leather were unaffected by increase of temperature in the dryer. Thus the aforesaid corrective factors include corrections for the variation in rate at which moisture moves to the surface of the shoe material in response to temperature changes.

55 In the accompanying drawings:

Fig. 1 illustrates diagrammatically a typical dryer;

Fig. 2 shows a control unit for the temperature of the air supplied to the dryer;

60 Fig. 3 shows a typical chart by which the setting of the control unit is determined; and

Fig. 4 illustrates a temperature-relative humidity diagram by which the chart is prepared.

The shoes in process are advanced through the tunnel 10 of the dryer shown in Fig. 1 by a conveyor 11 driven at a pre-selected rate of speed by suitable means (not shown). A stream of air is set up in the tunnel by a blower 15 which draws air from the room and passes it over a heater 16 and through a conduit 17 into the tunnel 10. The speed of the air stream so set up is determined by the blower and held at that uniform rate previously found to be most efficient.

75 The heater 16 may be of any desired type, pref-

erably steam or electric, and is regulated by a control unit 20. The structure of this unit is not shown in detail since it may be varied to suit conditions. The control unit 20 includes a panel 25, shown in Fig. 2, upon which is mounted a dry bulb thermometer 26 and a humidostat 27. The readings of these instruments give the temperature and relative humidity of the air as it enters the dryer.

Also mounted on the panel are a chart 28 and a regulator switch 29. The chart 28 (Fig. 3) embodies a plurality of vertical columns 30 each headed by a temperature reading and a plurality of horizontal columns 31 each headed by a relative humidity reading. The columns 30 and 31 cross to define a plurality of squares 32 in which are placed numbers which indicate the setting of the switch 29 that regulates the temperature of the drying air stream in the tunnel 10.

The numbers in the squares 32 are determined from the temperature-relative diagram set forth in Fig. 4. Such a diagram is one with which engineers in the drying field are familiar and is here shown so that the procedure by which these numbers are determined will be clear to one skilled in this art.

The maximum rate of drying of leather, or in other words the minimum percent of humidity of the drying air varies with the tannage and cut of the leather. It will be here assumed that for the leather to be treated the drying air must have a humidity of at least 15%. Selecting the atmospheric conditions generally prevailing in the particular locality in which the dryer is to be used, e. g. a dry bulb temperature of 70° and a relative humidity of 41% I locate the point 50 on the 15% relative humidity line. It is essential that the rate of drying be held constant although the temperature may vary and, as pointed out above, such variance in temperature affects the drying of the leather in two respects. First, the rate of diffusion of the moisture from within the leather increases with the temperature. Second, the rate of drying outside the dryer increases with the temperature and consequently the amount of additional drying necessary within the dryer to maintain uniform temper of the leather decreases. These factors for the leather to be dried are represented by the sloped lines 51 and 52 drawn through the point 50. The lines 51 and 52 thus represent the corrective factors involved in the determination of the numbers in the squares 32. The algebraic sum of these factors is the line 53 drawn through the point 50 so that this line represents the composite corrective factors and is used in the determination of the numbers as will now be described.

I will consider first a condition where the atmosphere has a dry bulb temperature of 80° and relative humidity of 50% and find the point 55 at the intersection of those lines on Fig. 4. From that point 55 is drawn a horizontal line 56 which intersects successively lines on the diagram at points 57, 58, 59 and 60. A vertical line from the point 58 at which the horizontal line 56 crosses the composite corrective factor line 53 crosses the temperature line at 116, and that number is inserted in the square 32 common to an atmosphere of 80° temperature and 50% humidity.

The other numbers on the chart 28 are similarly derived and a chart prepared for the particular dryer under consideration. Obviously changes in the amount of moisture to be ex-

tracted from the shoes, the length of the dryer, the speed of travel of the shoes through the dryer, the velocity of the drying air, the relative humidity to be maintained in the dryer, the tannage and cut of the leather, etc. require that a chart be prepared for each dryer. Once prepared, however, the dryer can readily be regulated so that the shoes traveling therethrough are presented to the operating station associated with that dryer in the desired temper regardless of atmospheric conditions.

While this invention has been shown and described in connection with a single installation, it will be understood that it is not limited thereto but is applicable to other installations and uses within the spirit and scope of the invention as set forth in the following claims.

I claim:

1. The process of manufacturing shoes which comprises wetting shoe parts, assembling the shoes at a series of successive operation periods in the open air and with air dryers removing portions of the moisture between two adjacent operations, characterized by determining under normal atmospheric humidity and temperature conditions the amount of moisture normally lost in the manufacturing process through the first of two open air operation periods, determining the amount of additional moisture which must be removed before the second operation can be properly performed, determining the drying time necessary to remove this additional moisture under average temperature conditions in a dryer with

high uniform velocity, and then, with the artificial drying time and air velocity fixed, so varying the drying temperature and consequently the drying air relative humidity, as atmospheric humidity and temperature conditions change, that the total moisture removed in the open air operation and the drying periods is always constant, thereby taking into account the effect of changing temperatures upon the rate of diffusion of the moisture out of the leather.

2. In that process of making shoes which comprises wetting shoe parts, assembling the shoes at a series of successive operations performed in atmospheric air, and introducing an atmospheric air dryer into said series of operations, the steps of determining the average amount of moisture normally lost during the manufacturing operations in the atmospheric air prior to the dryer, determining the amount of additional moisture which must be removed by said dryer to insure that the shoes be at the temper best suited for the operation next following the dryer, determining the drying time necessary to remove such additional moisture under average temperature conditions and then, while holding the dryer time fixed, so regulating the temperature of the atmospheric air in the dryer in a predetermined manner that the total amount of moisture removed in the atmospheric air operations and in the dryer is always constant.
